Primary Examiner — Austin Murphy

(57) **CLAIM**

The ornamental design for a portable power saw machine with support, as shown.

DESCRIPTION

FIG. 1 is a perspective view showing my new design.

FIG. 2 is a front view thereof.

FIG. 3 is a rear view thereof.

FIG. 4 is a top view thereof, and,

FIG. 5 is a right end view thereof.

FIG. 6 is a left end view thereof; and,

FIG. 7 is a bottom view thereof.
